UNITED STATES PATENT OFFICE.

WILLIAM J. GLUECK, OF EAST ST. LOUIS, ILLINOIS.

CARPENTER'S TOOL.

1,253,957.

Specification of Letters Patent. Patented Jan. 15, 1918.

Application filed December 18, 1914. Serial No. 877,891.

To all whom it may concern:

Be it known that I, WILLIAM J. GLUECK, a citizen of the United States of America, residing in East St. Louis, in the county of 5 St. Clair and State of Illinois, have invented certain new and useful Improvements in Carpenters' Tools, of which the following is a specification.

The object of this invention is to provide 10 an improved tool of such design and construction that quick and accurate gaging can be done in certain branches of carpentry, such gaging being heretofore done in a crude manner in which no accuracy 15 could be relied on.

Other and further objects will appear in the specification, and be specifically pointed out in the specification, reference being had 20 to the accompanying drawings exemplifying the invention, and in which,

Figure 1 is a perspective view of this improved tool.

Fig. 2 is a vertical section taken on the line II—II, Fig. 1.

25 Fig. 3 is a horizontal section taken on the line III—III, Fig. 2.

Fig. 4 is a perspective view of this improved tool in adjusted position from that shown in Fig. 1 to meet the requirements of 30 another class of work.

Fig. 5 is a perspective view of a portion of a wall showing this improved tool used in laying baseboarding.

Fig. 6 is an enlarged horizontal section 35 taken on the line VI—VI, Fig. 5.

Fig. 7 is a view of an upper corner of a doorway showing this improved tool as used in taking a measurement on a casing board for said doorway.

40 Fig. 8 is a view similar to Fig. 7, showing this improved tool in a position for taking a measurement on a door casing, which measurement will be flush with the top of the doorway.

45 Fig. 9 is an enlarged section taken on the line IX—IX, Fig. 7.

Referring to the drawings: This improved tool comprises a head block 1 having a bifurcation 2. Mounted in said bifurcation 50 is an extending member 3. Secured to one side of the head block 1 is a member 4. These members 3 and 4 are arranged parallel to each other, and are susceptible to adjustment, there being a longitudinal slot 5 formed in the member 4. Adjacent one end

of said slot on one side thereof is a pair of notches 6. Formed adjacent one end of the member 3 is a pair of slots 7. These members 3 and 4 are secured to the head block by a pair of bolts 8. Each of said bolts extends through each of said slots 7 of the member 3 and the slot 5 of the member 4. There are thumb nuts 9 for clamping the members 3 and 4 securely to said block 1.

Referring to Figs. 5 and 6, which illustrate the use of this improved device when laying baseboarding, it is the general practice in carpentry to first secure the base blocks 10 in their proper positions against the wall 11. The baseboard 12 is shoved at 65 one end against one of the base blocks 10, and the opposite end of the baseboarding is laid against the face of the opposite base block. This improved tool is then engaged over the base boarding by 70 having the members 3 and 4 straddle said baseboarding, one of the members engaging against the second mentioned base block and a pencil is then engaged against the edge of the outside member, as shown at A, 75 so as to draw a line across the base boarding 12. This will give the correct length of the baseboarding so when it is cut off on the marked line it will fit snugly between the base blocks.

In using this improved tool for putting the casing around doors or windows, or the like, if it is desired that a margin be given on the door frame, the tool is adjusted to the position shown in Fig. 4. This adjustment is done by loosening the thumb nuts 9 of the bolts 8 and then sliding the member 4 on the bolts longitudinally until the bolts will engage the notches 6. Then the member 3 is moved to one side until the bolts 95 engage the opposite end of the slots 7. Then the thumb nuts are screwed down. If it is desired, gage lines such as 13 can be located on the members 3 and 4 at portions B of said members. This improved tool 100 being in the adjusted position just described, when a casing board 14 is engaged at one end against the floor or block (not shown) the head block 1 of the tool is abutted against the under side of the top of the doorway. The member 4 will then extend across said board, see Fig. 7, and will be in a position so a line can be drawn across said board 105 which will designate the place to cut so said board will fit snugly against the head casing 110

board of the doorway. In getting a measurement for a casing board on the opposite side of the doorway, the tool is turned over and the member 3 then will be engaged 5 across the casing board, as just related of member 4. It is therefore seen that the adjustment of the bolts 8 in the notches 6 and slots 7 gives an adjustment for the marginal measurement of the casings of doorways. If desired, this improved tool may 10 be used to get a measurement for doorways which are to have the casings flush with the edge of the doorway (see Fig. 8). Then the bolts are not adjusted in the notches 6 and slots 7, but the edges of the members 3 and 4 are flush with the edges of the head block 1.

In a tool of this improved character it has been found essential in carpentry to have 20 the width of the parallelly arranged members 3 and 4 equal to the thickness of the head block 1. As in taking a flush measurement, as shown in Fig. 8, it is necessary to provide a firm seating base to the head block. 25 This firm seating base is provided when the parallel members 3 and 4 are arranged horizontally with the head block as shown in said Fig. 8, in which one of the edges of the member 3 is shown bearing against the 30 same surface of the work as is one of the faces of the head block, the top edge of the member 4 providing the flush measurement relative to the work to which the top edge of the member 3 is engaging.

35 From the aforesaid description, it is seen how a tool of this improved construction can be used in many branches of carpentry, and when so used, a very solid abutment is given to the tool, which will insure a positive gage 40 to be extended over the work that is to be marked so that accuracy of gaging will be the result.

What I claim is:

1. A tool comprising a head block, a pair 45 of parallelly extending members secured to said block, each of said members being of a width equal to the thickness of said block so that the side edges thereof will be flush with said block.
- 50 2. A tool comprising a head block, and a pair of parallel members extending therefrom, each of said members having a width equal to the thickness of said block, and means whereby said members can be adjust- 55 ed relative to said block.
- 55 3. A tool comprising a head block, and a pair of parallel members of equal length ex- 60 tending therefrom, one of said members being adjustable longitudinally of said block so that said adjustable member can be ex- 65 tended from said block in a direction oppo- 70 site to said other member, said other mem-

ber being adjustable transversely of said block.

4. A tool comprising a head block, a pair 65 of parallel members adjustably mounted thereon, said members being of equal length and having a width equal to the thickness of said block, one of said members having a transverse adjustment, and the other said member having a transverse and a longitudinal adjustment.

5. A tool comprising a head block, a pair of spaced apart parallel members extending 75 from one end of said block, each of said members having a width equal to the thickness of said block so that the side edges thereof will be flush with said block, one of said members adapted to be extended from the other end of said block, and means for 80 clamping said members to said block.

6. A tool comprising a head block, a pair of spaced apart parallel members extending 85 from one end of said block, each of said members being of a width equal to the thickness of said block, one of said members adapted to be extended from the other end of said block, and means whereby said members are adapted to be adjusted transversely 90 of said block.

7. A tool comprising a head block, a pair of spaced apart parallel members extending 95 from one end of said block, each of said members being of a width equal to the thickness of said block, one of said members having a slot formed thereon so that said member can be extended from the other end of said block, and means whereby said members are adapted to be adjusted transversely 100 of said block.

8. A tool comprising a head block, said block having a pair of flattened surfaces formed thereon, a substantially flattened member mounted on each of said surfaces of said block, said members being parallelly 105 arranged relative to each other and extending from said block, one of said members being adjustable transversely and longitudinally of said block.

9. A tool comprising a head block, said 110 block having a pair of flattened surfaces formed thereon, a substantially flattened member mounted on each of said surfaces of said block, said members being parallelly arranged relative to each other, and extending from one end of said block, and means carried by said block whereby one of said members can be extended from the other end of said block and adjusted transversely of said block.

WILLIAM J. GLUECK.

In the presence of—

M. C. GLUECK,
H. G. FLETCHER.
